UNITED STATES PATENT OFFICE.

JOSEPH NESSING, OF MERIDEN, CONNECTICUT.

DESIGN FOR A WEAPON.

49,220.

Specification for Design.

Patented June 20, 1916.

Application filed May 1, 1916. Serial No. 94,838. Term of patent 7 years.

To all whom it may concern:

Be it known that I, JOSEPH NESSING, a subject of the Emperor of Austria-Hungary, residing at Meriden, in the county of New Haven and State of Connecticut, have invented a new, original, and ornamental Design for a Weapon, of which the following is a specification, reference being had to the accompanying drawing, forming part thereof.

The figure is a view in perspective of a weapon, showing my new design.

I claim:

The ornamental design for a weapon, as shown.

JOSEPH NESSING.

Witnesses:

JOHN L. CEYRA,
F. B. DIEL.

Copies of this patent may be obtained for five cents each, by addressing the "Commissioner of Patents, Washington, D. C."
